UNITED STATES PATENT OFFICE.

FREDERICK L. M. BOOTHBY, OF TILFORD, ENGLAND.

AIRSHIP.

Application filed April 8, 1924. Serial No. 705,113.

To all whom it may concern:

Be it known that I, FREDERICK LEWIS MAITLAND BOOTHBY, a British subject, residing at Tilford, Surrey, England, have 5 invented certain new and useful Improvements in and Relating to Airships, of which the following is a specification.

In connection with the piloting of airships it is necessary to counterbalance the 10 reduction in the weight carried, due to the consumption of the liquid fuel used by the engines. It has been proposed to effect this by releasing a proportionate amount of the inflating gas, which of course, reduces the 15 lifting capacity of the airship. In connection with hydrogen inflated airships it has further been proposed to utilize the gas so released, by consuming it in the engines conjointly with the petrol.

20 Apart from the economy effected by this system of utilizing the gas, this utilization of hydrogen with petrol, by reducing the consumption of petrol enables the duration of the voyage to be extended, and notwithstanding that it allows of a cheaper and heavier fuel oil being used, produces a 25 higher efficiency of the engine.

The present invention relates to systems 30 of this type, but as obviously the system is limited to airships which contain a combustible gas, one of the objects of the invention is to use a sufficient amount of combustible gas in an airship which otherwise is inflated with a non-inflammable gas, such as, for 35 instance, helium.

According to one feature of the invention, therefore, this is effected by replacing a part of the non-inflammable inflating gas by hydrogen.

40 In its application to airships in which the inflation gas is contained in separate bags or compartments, bags specially intended for the hydrogen are arranged within or between some or all the bags containing the 45 non-inflammable inflating gas, and in such a manner that they are preferably completely enveloped in or surrounded by the said non-inflammable gas. The hydrogen containers are by preference located in the vicinity of the fuel and ballast carrying parts of the airship.

In airships generally, in which hydrogen is contained in separate bags or compartments, it is not desirable to draw the gas 55 for consumption in the engine and for ballasting purposes, equally from each com-

partment, and the invention has, therefore, the further object of enabling the hydrogen to be drawn by any one or more engines from any one or more of the compartments or group of compartments, in accordance with the desired trim of the airship; for example, less may be drawn from those compartments which support permanent weights, such as the tail, fins and mooring gear, while a greater proportion may be taken from those which support the fuel and ballast.

The navigator will thus be enabled to alter the trim of the airship while in flight; as, for example, when coming to a mooring mast or column, when it is desirable that the airship should be light forward, or for normal flight when maximum efficiency is obtained with the airship trimmed so as to be horizontal with neutral buoyancy.

Broadly such a control is attained by means of a system of pipes, comprising a main, from which valve or cock controlled branches lead on the one hand to the hydrogen containers and on the other hand to the engines, so that any one or more of the engine branches may simultaneously or alternately be placed in communication through the main with any one or more of the gas 80 bag branches.

Incidentally the said pipe system may also serve for filling purposes or for equalizing the contents in the several gas bags.

The accompanying drawings illustrate 90 diagrammatically arrangements embodying the invention as applied to various types of airships.

Fig. 1 is a longitudinal section of an airship inflated by gas of the non-inflammable character and adapted in accordance with 95 and for the purposes of the invention, while

Fig. 2 is a cross section of the same on the line II—II of Fig. 1.

Fig. 3 is a cross section of a similarly inflated airship in which the gas bags are 100 surrounded by a further protective chamber suitable for example to be filled with the non-inflammable exhaust gases from the engine, according to the method described in my patent application Serial No. 690,205.

Fig. 4, shows, in a similar view to Fig. 1, a modified arrangement.

Fig. 5 is a longitudinal section of an airship inflated by hydrogen gas.

Fig. 6 a cross section of the same and

Fig. 7 a cross section of an airship in which the hydrogen gas bags are surrounded

by a space or chamber for non-inflammable gas.

Figs. 8 and 9 show two arrangements of the control cocks, when not directly accessible, as for instance, in the trunks between the air bags.

Fig. 10 shows an example of a safety device for preventing back firing from the engine, while

10 Fig. 11 shows an example of a seal or trap in the hydrogen supply pipe to the engine.

No framework or net over the airship has been shown in the drawings, in order 15 to render them clear, but such of course may be used.

20 The type of airships shown in Figs. 1 to 3 is of the kind which is inflated by gas of a non-combustible character, for example, helium, and adapted in accordance with and for the purposes of the invention to receive a limited volume of hydrogen or other combustible gas.

25 In the arrangement shown in Figs. 1 and 2 gas bags or compartments A containing helium are enclosed in an outer cover B, and connected to atmosphere by means of relief valves A', automatically responding to excessive pressure in the bags and discharging 30 the gas into the trunks A².

35 In the interior of some (not necessarily all, as shown in Fig. 1) of the helium containers, so as to be completely surrounded thereby, or between the helium containers, as shown in Fig. 4, are arranged gas bags D for the reception of hydrogen, such bags D having an aggregate capacity somewhat in excess of the volume required for counter-balancing the total initial load of liquid fuel 40 carried by the airship. The capacity may be increased so as to allow release of the cheaper hydrogen gas for manoeuvring purposes instead of the costly helium.

45 Each of the hydrogen containers is connected to the atmosphere by means of a conduit D' passing through the helium container A and the outer cover B, and provided with a manoeuvring valve D².

50 In order to prevent collapse of the hydrogen bags D their envelopes are supported, approximately to the extent of their upper halves, by stays a, as shown diagrammatically in Figures 2 and 3, as otherwise, when the hydrogen was withdrawn, the bags would 55 collapse to the bottom of the containers A.

60 Each of the hydrogen containers is connected by a valve or cock-controlled branch pipe 1, terminating approximately in the centre of the bag, to a main pipe 3, which is arranged in the keel E of the airship, and is connected by valve or cock-controlled branch pipes 4 to the engines located in the cabins F.

65 The main pipe 3 is provided at one end with a union adapted to connect it to the hy-

drogen producer or reservoir, but is normally shut by the stop cock of valve 3^a.

A similar pipe system 5, 6 (Figure 2) may be provided for filling the helium bags A, no connections to the engines being, however, 70 provided.

The type of airship represented by Fig. 3 and the arrangement shown therein is similar in every respect to the one hereinabove described in relation to Figs. 1 and 2, except 75 in so far that a chamber C, formed between and around the helium bags A and the outer cover B, is adapted to be filled with non-inflammable gas, for example, the exhaust gas from the engines supplied thereto by 80 means of the pipe 7, and in accordance with the method and arrangement described in my patent application Serial No. 690,205, the main object of the exhaust gas in this 85 instance being to keep the fabric moist.

Fig. 4 shows an arrangement in which the hydrogen bags D are only partly surrounded by the helium containing bags A, while

90 Fig. 5 shows the invention as applied to an airship in which the several gas bags A, arranged within the outer cover B, are inflated with hydrogen.

95 A modification is here shown in Figure 5, in the arrangement of the pipe system. Instead of carrying the branch pipes (such as 1 in the preceding examples) vertically from below directly into each hydrogen bag, stand pipes 2 are here carried up vertically in the trunks A² arranged between 100 each pair of bags A, horizontal valve or cock controlled branch pipes 1 leading from the said stand-pipes 2 approximately to the centre of each of the adjoining bags. The engines are connected to the main 3 by 105 branch pipes 4, in a like manner as in the examples illustrated in Figs. 1 to 3.

110 In Fig. 7 the hydrogen bags A are protected by a layer of non-inflammable gas (such as for instance the exhaust gas hereinbefore referred to in connection with Fig. 3) contained in the chamber C and supplied thereto through the pipe 7. In all other respects the arrangement is analogous to that illustrated in Figs. 4 and 5.

115 It is evident that the two arrangements of the branch pipes leading into the hydrogen bags shown in Fig. 1 and Fig. 4 respectively are not restricted to the particular type of airship indicated in the drawings.

120 It is to be observed that the branch pipes 1 are arranged to reach well into the centre of the hydrogen bags, so that in the event of air flowing up the tube into the bag and there catching fire, the flames would be 125 clear of the fabric and no serious harm would be caused.

130 The whole system of pipes must be constructed of sufficiently strong material so as to prevent collapse, due to the pressure of

the walls of the gas bags when not fully inflated.

By opening the cocks 1^a in the branch pipes 1 leading to the selected hydrogen bags 5 A, and the cock or cocks 4^a in the branch pipes leading to the engine or engines for the time being at work, the latter will by their suction draw off the hydrogen from the desired hydrogen containers. The navi-

10 gator is thus enabled to control the trim of the airship in the most efficient manner.

In order to use such a pipe system for inflating the hydrogen bags the cocks 4^a are turned off, the cocks 1^a are turned on and 15 the main 3 having been connected to the gas producer or reservoir the turning on of the main cock 3^a allows the gas to flow to the several bags.

The inter-connection of the several gas 20 bags by means of the main 3 and the branch pipes 1 or 2 and 1, enables the volumes of gas in the several gas bags to be equalized, should one or more have leaked through damage, or if such volumes have become 25 unequal from other causes. This can be effected by opening the cocks 1^a leading to the emptier compartments and to one or more of those from which it is desired to replenish them. By then causing the airship 30 to rise until the gas in the most charged compartments is at a slight pressure but insufficient to open its automatic relief valve, gas will flow from such compartments into the less filled compartment or compartments.

In the case of airships which are protected by a layer of non-inflammable gas, provided around the gas bags in a chamber such as C, (Figs. 3 and 7) the pipes to the 40 gas bags may be led along the inert gas space.

The cocks 1^a (Figs. 4 to 6) arranged in the usual trunk A² may be operated by means of chains, wires or rods 8; or the fabric may be provided with a bay 9 allowing the cock handle 1^a to be gripped through the fabric 10, as shown in Fig. 8; or the stem of such cock may pass through the fabric 10 and be held gas tight therein by glands 50 11 as shown in Fig. 9.

Fig. 10 shows a valve destined to be fitted into the pipe by which the hydrogen is supplied to the engine, and constructed with a view to prevent back-firing from the engine into the gas bags. It consists of a thimble 12 made of porous porcelain, papier mâché or other material which will readily permit the hydrogen gas but not air to percolate. This thimble 12 is fitted over the end of the branch pipe 4 and forms a chamber 13 in front thereof. A cylindrical casing 14 protects the said thimble and connects the pipe 4 to the suction pipe 15 of the engine. A metal cap 16 slidably fits over, and is held by a light spring 17 in

contact with the head of the thimble 12. Its shouldered-off sleeve portion 16^a, of larger diameter, is slidable in the housing 14 over apertures 21 therein and is provided in its shoulder with apertures 18, which 70 establish communication between the annular chamber 19 formed between the thimble 12 and the sleeve 16^a and the chamber 20 surrounding the cap 16.

The suction of the engine automatically 75 regulates, according to requirements and speed, the amount of gas drawn into the engine. By drawing the cap 16 against the spring 17 it regulates the exposed area of the porous thimble 12 through which the 80 gas filters into the chamber 19 and proportionately uncovers the air inlets 21 in the housing 14 thereby producing a uniform mixture which is drawn off through the 85 apertures 18.

An alternative simpler form of safety valve is illustrated in Fig. 11, which is suitable for use when the gas is brought vertically from below to the engine. It consists of an enlarged chamber 22 formed between 90 the gas supply pipe 4 and the suction pipe 15 of the engine; in which chamber a light metal disc 23 of smaller diameter than the chamber, loosely rests over the inlet opening of the pipe 4. The disc 23 is lifted by the suction of the engine but its movement is limited by the pins 24 projecting from the wall into the chamber 22.

I claim:—

1. A motor-driven airship comprising an 100 outer covering, a series of gas bags within said covering, vertical trunks between said gas bags, engines for driving said airship, a series of branch pipes extending upwardly in said trunks and communicating with the interiors of said gas bags, controls for said pipes, a main pipe with which said branch pipes communicate and controllable connections between the main pipe and the engines substantially as described.

2. A motor-driven airship comprising an 105 outer covering, a series of gas bags within said covering providing a free space between the outer covering and the said gas bags, vertical trunks between said gas bags, engines for driving said airship, a series of branch pipes extending upwardly in the trunks and communicating with the interiors of said gas bags, controls for said pipes, 110 a main pipe with which said branch pipes communicate, a controllable connection between the main pipe and the engines, and means for introducing exhaust gases from the engines into said space, substantially as 115 described.

3. A motor-driven airship comprising an 120 outer covering, a series of gas bags within said covering, vertical trunks between said gas bags, a series of gas containers within 125 said gas bags, engines for driving said air-

ship, a series of branch pipes extending upwardly in said trunks and communicating with the interiors of said gas bags, controls for said pipes, a main pipe with which
5 said branch pipes communicate and controllable connections between the main pipe and the engines substantially as described.

4. An airship comprising a keel, engines thereon or attached to other parts of the
10 airship, an outer envelope, a plurality of gas bags within the envelope, vertical trunks

between the gas bags, smaller gas bags within or between some or all of the said gas bags, means for releasing the contents of the smaller gas bags, controllable means for 15 supplying the contents of any one or more of the smaller bags to the engines and means for storing light fuel, substantially as described.

In testimony whereof I affix my signature.

FREDERICK L. M. BOOTHBY.
